Inventor:
Richard Caffrey
By Paine Ladd, Atty's.

UNITED STATES PATENT OFFICE.

RICHARD CAFFREY, OF WHITE HAVEN, PENNSYLVANIA.

TRACK-GAGE.

SPECIFICATION forming part of Letters Patent No. 326,271, dated September 15, 1885.

Application filed June 16, 1885. (No model.)

To all whom it may concern:

Be it known that I, RICHARD CAFFREY, a citizen of the United States, residing at White Haven, in the county of Luzerne and State 5 of Pennsylvania, have invented certain new and useful Improvements in Railroad-Track Gages; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to gages for railway-tracks; and it consists in the construction of the same, as hereinafter fully described and claimed, so that the same gage used to fix the relative distance apart of the rails of the main 20 track may also fix the relative positions of the guard-rails which are used where a siding diverges from the main track.

25 In the drawings, Figure 1 is a side elevation of the gage, showing portions of the rails to which it is applied in cross-section. Fig. 2 is a plan view of the gage. Fig. 3 is also a plan view, and shows a modification in the method of forming the ends of the gage.

30 Similar letters indicate corresponding parts in all the figures.

A is a frog, consisting of two wing or guard rails, *a a*, and the main-track rail B, which is here brought to a point. These rails are connected together by any suitable means commonly in use. B' is the other main-track rail, 35 upon which the car-wheels run.

C is a guard-rail, as commonly used opposite a frog, to keep the flanges of the car-wheels from running the wrong side of the 40 main-track rail B where brought to a point.

D is the track-gage, consisting of a rod provided with flattened ends, so that it may rest upon the tops of the rails, and having projecting portions depending from each end of it.

45 The outside of these depending portions, or the distance between the points *d d*, forms the gage for the main-track rails. The inside of

the said portions, or the distance between the points *d' d'*, forms the gage for the guard-rails.

In Fig. 3 the ends of the gage are forked, so 50 that the depending projections are duplicated. The use of this modification in the form of construction insures the gage being laid at right angles across the track. Another simple modification of the same device would be 55 to make only one end forked and leave the other end as shown in Figs. 1 and 2.

The gage as above described will be found simple and cheap to construct, and will be of very great use in making railroads, as it is of 60 the greatest importance that the guard-rails which guide the car-flanges at a siding should be placed at the same distance from the main-track rails, and also that they and the said main-track rails should be at the same 65 distance apart. This result can only be obtained by using a device which will gage all three distances at once or by repeated measurements.

Having thus described my invention, what 70 I claim as new, and desire to secure by Letters Patent, is—

1. A railroad track gage consisting of a bar provided with projections depending from the ends of it, so that the distance between the 75 outside of the projections forms the gage for the main-track rails and the distance between the inside of the said projections forms the gage for the guard-rails, substantially as and for the purposes set forth. 80

2. A railroad-track gage consisting of a bar forked at one or at both ends, and having projections depending from each end, so that the distance between the outside of the projections forms the gage for the main-track rails, 85 and the distance between the inside of the said projections forms the gage for the guard-rails, substantially as and for the purpose set forth.

In testimony whereof I affix my signature in presence of two witnesses.

RICHARD CAFFREY.
